UNITED STATES PATENT OFFICE.

JOSEPH T. ROBIN, OF NEW YORK, N. Y.

DESIGN FOR A SHOW-CASE.

SPECIFICATION forming part of Design No. 30,889, dated May 30, 1899.

Application filed March 31, 1899. Serial No. 711,288. Term of patent 14 years.

To all whom it may concern:

Be it known that I, JOSEPH T. ROBIN, a citizen of the United States, residing at New York, in the borough of Manhattan, county and State of New York, have invented and produced a new and original Design for Show-Cases, of which the following is a specification, reference being had to the accompanying drawing, forming a part thereof.

10 The leading or essential feature of my design for a show-case is the article shown and described. A represents the ends, B the back, and C the bottom thereof. The ends consist of triangular frames in which are fitted pieces

15 of glass. The front consists of a quadrangu-

lar frame in which is fitted a piece of glass. The bottom is shown as horizontal, the back as vertical, and the front as inclined from the top of the back to the front of the bottom.

What I claim as my design, and desire to 20 secure by Letters Patent, is—

The design for a show-case, substantially as shown and described.

In testimony whereof I have signed my name to this specification in the presence of 25 two subscribing witnesses.

JOSEPH T. ROBIN.

Witnesses:

H. COUTANT,
GEO. E. CRUSE.
